KNITTING MACHINE

Wilbur L. Houseman, South Orange, N. J., assignor to Standard-Trump Bros. Machine Co., Laconia, N. H., a corporation of Delaware

Application June 27, 1933, Serial No. 677,804

10 Claims. (Cl. 66—135)

This invention relates to a knitting machine and more particularly to a knitting machine of the rotary type in which patterns are produced by the individual wrapping of needles.

5 The most satisfactory type of circular knitting machine for the production of elaborate products is the rotary cylinder type inasmuch as in this type of machine the primary manipulations involved are those of the needles which are acted upon by relatively stationary elements. The control of these elements is of course most readily effected when they are stationary since direct connections to them can be made from stationary patterning mechanism. To produce individual 10 needle wrapping in a machine of this character, it is necessary that the wrap fingers cooperating with the various needles should revolve with them being actuated by stationary elements at various points to give them radial inward and outward movements to effect wrapping. Wrapping on a rotary needle cylinder machine accordingly involves the rotation of the yarn supplies for the wrap fingers. This can be readily effected, however, and makes the rotary needle cylinder type of machine more satisfactory than the rotary cam cylinder type. To produce more elaborate patterns than those which are possible by the association of a certain wrap finger with any particular needle, shogging is resorted to, involving the rotation of all of the wrap fingers relatively to the needles while nevertheless causing them to partake of the general rotation of the needles. In the rotary needle cylinder type of machine the shogging connections 15 themselves must be fairly elaborate in order to produce the differential angular shogging movements without interrupting the rotation of the parts. In one satisfactory form of arrangement an epicyclic gear train connects the wrap finger supporting head and the needle cylinder in such fashion that movements imparted to an intermediate portion of the train will produce shogging.

One drawback to the production of designs by shogging has been the limitations imposed by the requirements that shogging cannot take place while any yarn-carrying wrap fingers are in position between adjacent needles. In other words, shogging movements dare only occur when the wrap fingers are either inside or outside the needle circle to prevent bending or breakage. The result of this has generally been the necessity for avoiding wrapping on a certain panel of needles corresponding in angular extent to the angular motion of the needle cylinder, or the cams

of a rotating cam machine during shogging movements. In hosiery this unwrapped panel has generally been produced at the back of a stocking where it is least noticeable. Nevertheless, it is objectionable particularly since its width is generally substantial, depending directly upon the time required for forward or backward shogging, whichever is the greater.

The relatively elaborate connections required to produce shogging in the rotary cylinder type of machine increase the time required for both forward and backward shogging movements. The unwrapped panel is accordingly usually of a substantially greater width than that which would be required in a rotary cam type of machine.

It is the broad object of the present invention to provide a machine of the rotary cylinder type in which shogging may be effected without interruptions in the wrapped design. Specifically this is carried out by producing wrapping at two points, the shogging being effected at a time when none of the wrap fingers is passing through the needle circle even though all of the needles may be wrapped.

It is a further object of the invention to provide for the production of designs under the control of a single patterning mechanism even though wrapping takes place at spaced points. The angle between the two wrap points is maintained at a minimum not only to permit the common control of wrapping at both points but also to provide a maximum freedom for manipulations of the needles during rotation other than those directly concerned with wrapping. The angle between the two wrap points is made small by providing in the combination a shogging means which effects the shogging movements both forward and backward during minimum angular rotation of the needle cylinder.

Other objects of the invention particularly relating to details of construction will be apparent from the following description read in conjunction with the accompanying drawings in which:

Fig. 1 is a right-side elevation of the machine partly in section and with various parts removed for clearness;

Fig. 2 is a vertical radial section through one side of the needle cylinder showing the relationship between the needles and jacks and operating mechanism therefor;

Fig. 3 is an enlarged vertical sectional view showing the wrapping mechanism and controlling devices therefor;

Fig. 4 is a horizontal section through the same;

Figs. 5 and 6 are elevations of two types of wrap fingers used in the machine;

Fig. 7 is a horizontal sectional view illustrating the driving gearing for the wrap finger supporting head;

Fig. 8 is an enlarged fragmentary elevation showing parts associated with ratchets controlling the carrier for the intermediate driving gearing of the wrap finger head; and

Fig. 9 is a diagrammatic developed view illustrating the relationships of the various controlling cams.

The machine which is of the rotary needle type comprises an elongated cylinder 2 mounted for

rotation about a vertical axis and provided with longitudinally extending slots adapted to slidably receive needles 6 provided with butts 8 of different lengths as is usual in this type of machine. Also, sliding within the slots of the needle cylinder are intermediate jacks 10 provided with butts 12 and lower jacks 14 provided with removable butts 16 and formed at their lower ends with cam engaging ledges 18. The needles and intermediate jacks are designed to slide vertically within

the slots, the needles being held in the slots by the use of usual spring bands while the intermediate jacks are held therein by engagement with the cylindrical surfaces of certain cams, as will be hereafter pointed out. The lower jacks 14 are adapted to slide and also pivot in vertical radial planes about points intermediate their upper and lower ends. To accomplish this, the lower jacks have their inner edges formed as shown in Fig. 2 providing a point 19 about which they may pivot when acted upon by suitable cams in a manner which will be hereafter pointed out. These lower jacks are held in position by a single spring band which, however, is not relied upon to maintain the jacks in any definite position al-

though, as will be clear from the drawings, there will be a tendency for the spring band to hold the jacks with their lower ends projecting outwardly.

The needle cylinder has secured thereto the usual gear 20 which is driven through an idler by the driving gear 50 controlled by suitable mechanism of the usual type to provide both rotation and reciprocation. The gear 20 is mounted in the portion 22 of the frame.

To provide a support for various elements of the mechanism, there is provided a platform 24 which is supported from the lower portion 22 of the frame by suitable posts. Bracket 26 supported by the platform 24 carries a shaft 28 upon which the latch ring supporting bracket 30 is pivoted, this bracket carrying a latch ring 32. The supporting bracket has pivoted to its forward portion a hook 34 engageable with a pin 36 carried by an upstanding bracket 38 to maintain the latch ring in its lowered position. Manipulation of the hook 34 will release the hook from the pin 36 so that the latch ring may be raised in the usual manner, a suitable spring being provided to counterbalance its weight and adapted to hold it open. The usual cam ring 40 containing the cams for controlling the sinkers is provided, the cam ring having the usual freedom for oscillatory movements limited by engagement of stops with the post 38.

A bracket 42 pivoted on the shaft 28 is provided at its forward end with a downwardly extending portion 44 provided with openings through which are adapted to project headed screws designed to thread into the latch ring supporting bracket 30. A spring 47 counterbalances the weight of the bracket 42 so that this

bracket will tend to remain in the position illustrated in Fig. 1 except when held down by the screws. When secured by these screws to the latch ring support, the latch ring and the bracket 42 may be raised as a unit by freeing the hook 34 from the pin 36.

The shaft 48 which carries the gear 50 projects upwardly and carries at its upper end a gear 52 meshing with a pinion 54, the shaft of which has a universal connection with one element 56 of a split shaft to which element the other element 58 is splined by the use of a key and slot connection. The upper element 58 has a universal connection with a shaft 59 carrying a gear 60. The shaft 59 is journaled in a support 62 which is in turn journaled upon an annular portion of the bracket 42. The gear 60 meshes with a gear 64 which is attached to the wrap finger supporting assembly journaled in the bracket 42. This assembly includes a plate 66 provided with supporting pins upon which bobbins 70 may be mounted. Above these bobbins there is a plate 68 supported by an upwardly extending tube 67, the plate 68 being provided with tension members designed to tension the yarns from the bobbins 70 which pass upwardly and then downwardly through the tube 67 and then through the eyes of the wrap fingers. The wrap fingers illustrated at 80 and 81 are carried by a head forming the lower portion of the assembly and consisting of a preferably single member providing cylinders 82 and 83 having aligned vertical slots therein, there being between these cylinders a groove 84 having a semi-circular radial cross section to receive semi-circular projections 86 of wrap fingers and thereby provide a pivot for the same. The wrap fingers are held within the slots 82 and 83 by means of a spring band 80.

The lower ends of the wrap fingers are twisted in the usual fashion so that as a wrap finger moves outwardly through the needle circle it passes to one side of the needle with which it is to cooperate by reason of the cam action of the hook of the needle on its end; and then on its return passes to the other side of that needle again due to the camming action of the hook of the needle.

The wrap fingers 80 and 81 differ from each other in that the former is provided with a lower butt 85 while the latter is provided with an upper butt 87. In a normal set-up of the machine wrap fingers 80 might be provided in half the circle while fingers 81 could be provided in the remaining portion of the wrap finger circle. Various fingers might be either omitted or merely unthreaded. There will, however, be required through at least a small portion of the wrap finger circle an arrangement permitting shogging without breakage of needles or fingers. This will be clearly indicated hereafter.

To rock the wrap fingers outwardly by engagement with their upper butts there are provided two cams 90 and 92 pivoted on a post 94 and urged to an inactive position by springs 96 and 98. The active butt engaging ends of the fingers 90 and 92 are angularly spaced as illustrated, this spacing being determined as hereafter pointed out, by a consideration of the time required for the production of shogging movements and the extent of these movements.

To selectively move the fingers 90 and 92 into operative position there are provided cams 100 and 102 urged downwardly by springs 104 and 106 and individually controlled by levers 108 and 75

110 acted upon by motion transmitting levers 112 whose positions are controlled by cams 114 on the main cam drum. During normal rotary knitting when all of the needles may be wrapped, both the cams 90 and 92 are required to be in active position. One of them, however, may be rendered inactive when it is desired to produce a plain sole on a stocking and both may be rendered inactive during reciprocation to avoid engagement with the wrap fingers.

To effect the return of the lower ends of the wrap fingers inwardly of the needle circle after they are rocked outwardly by the cams 90 and 92 there is provided a cam member 116 provided with active faces 118 and 120 adapted to engage the wrap fingers below their pivots. Between the active portions 118 and 120, the cam 116 is cut away as indicated at 122 so that it does not interfere with the outward movements of the lower ends of the wrap fingers under the action of cam 92.

Referring to Fig. 7 the carrier 62 which has been referred to above as supporting the pinion 60 is shown as provided with an extension 124 adapted to carry ratchet plates. The carrier 62 is normally urged in a clockwise direction as viewed in plan by a weight 126 connected to it by a cable 128 passing over a pulley 130.

In Fig. 8 there is illustrated the most desirable means for producing shogging movements of the carrier 62. This mechanism is essentially that described and claimed in the application of Harold E. Houseman, Serial No. 668,924, filed May 2, 1933, to which reference may be made for details of construction and operation. The extension 124 carries ratchet plates 146, 148 and 150. The teeth of the plates 146 and 150 are directed in one direction, namely to the left, as viewed in Fig. 8, while the teeth of the plate 148 are directed in the opposite direction. A stud 152 carried by an extension of the bracket 42 provides a journal for three levers 154, 156 and 158, these levers being provided with extensions carrying stop screws 159 urged into contact with an extension of the frame by individual springs 161 which urge the levers 154, 156 and 158 counter clockwise in opposition to actuating mechanism of the type illustrated in the Harold E. Houseman application referred to above. At its upper end the first of these levers carries a stud 160 on which is journalled a pawl 162 the nose of which is urged towards the teeth of the ratchet plate 146 by means of a spring 164 connected between the pawl and a post carried by the lever 154.

A pin 168 carried by the pawl is arranged to engage a cam 170 carried by a fixed bracket 172 so that the pawl is held out of contact with the teeth when in its retracted position to which it is urged by its spring 161. As the lever 154 is moved clockwise, as viewed in Fig. 8, the pawl 162 will move to the right so that it will engage a tooth of the ratchet 146 as the pin 168 rides off the cam 170. The cam 170 is provided primarily to normally hold the pawl 162 away from the teeth to permit reverse movements of the carrier.

A rod 174 carried by the lever 154 is provided with a spearhead adapted to engage a cam 176 carried by a detent 178 mounted on a fixed stud 180 and urged by a spring to bring its nose into engagement with the teeth of the ratchet plate 148. A lateral extension of the arm 154 pivotally supports a lever 177 which is urged by a strong spring 181 into engagement with a stop carried by the extension. The lever 177 is in

horizontal alignment with a sloping lefthand surface of the pawl 178. The arrangement of the parts is such that as the rod 174 advances during forward movements of the pawl 162 the spearhead engages the cam 176 to disengage the detent 178 from one of the teeth of the plate 148 just prior to the engagement of the pawl 162 with a tooth of plate 146. As the spearhead moves further its point passes over an inward point of the cam 176 thereby releasing the detent 178 permitting it to again move between the teeth of plate 148 as soon as the pawl 162 has advanced the carrier to such extent as to move the last engaged tooth beyond the nose of the pawl 178. To insure that the pawl 178 moves inwardly, the lever 177 is arranged to engage it to provide a force in addition to that exerted by its spring. The pawl is accordingly in position to engage the next tooth of plate 148 before the pawl 162 reaches its extreme forward position. The detent 178 is not only provided for the purpose of properly aligning the wrap fingers with the needles but additionally to hold the carrier in position during reciprocation at which time the weight 126 might be insufficient to hold it sufficiently rigidly to prevent objectionable vibration. The use of the detent 178 also serves to reduce to a minimum the period of relative movement between the wrap finger carrying head and the needle cylinder, since the forward shogging movement of the head is arrested in the forward movement so that alignment of fingers and needles immediately occurs and does not need to await the settling back of a tooth upon a detent 186 or 188 after an overrun. The angular spacing of the two wrap points is thereby made a minimum with a resultant simplification of construction and control.

Also journalled upon the post 180 are detents 186 and 188 of different lengths as will be evident from Fig. 8. These detents are arranged to alternately engage teeth of the ratchet plate 150 which, as illustrated, are double the length of teeth of the ratchet plates 146 and 148. The detents hold the plate 150 in opposition to the effort of the weight 126. The detents 186 and 188 are yieldingly held in operative engagement with the teeth by means of springs 192 reacting between them and a pin fixed on the machine frame. The lengths of the pawls 186 and 188 are such that as they are alternately tripped the carrier may move backwardly in steps under the action of the weight through the angular spacing of the teeth on plate 146.

Members 194 and 196 are carried by the upper ends of levers 156 and 158, respectively, and are designed to engage the pawls 186 and 188, respectively, to trip them out of engagement with the teeth of plate 150. The operation is such that the members 194 and 196 are alternately moved so that backward steps of proper angular amount are produced by the alternate freeing of the detents 186 and 188 from the teeth. The control of the levers 154, 156 and 158 by pattern mechanism is identical with that illustrated in the Harold E. Houseman application referred to above and need not be described for the purposes of the present invention.

The machine to which the present invention is applied is, except for the shogging features, similar to that illustrated in the application of Stanley R. Shelmire, Serial No. 623,057, filed July 18, 1932. It includes, for example, means for manipulating a double sole yarn and also means for forming gusset toes in stockings. Certain of the

- cams for effecting these operations are indicated in Fig. 9 but need not be referred to in detail since they form no essential part of the present invention. The presence of these means, however, 5 indicates the advantages of a rotary cylinder machine over a stationary cylinder machine inasmuch as the controls for effecting the various operations would be difficult to provide in the latter type of machine.
- 10 Referring specifically to Fig. 9, there is illustrated therein, in a diagrammatic fashion to show the angular relationships of the various parts, those cams which act upon needles, wrap fingers and jacks. The usual stitch cam set is 15 provided, as indicated, at 200, 202, 204 and 206. The needles in rotary knitting pass through the cams to the left as viewed in Fig. 9 rising over cam 204 during rotary knitting and being drawn down to form stitches by the cam 206.
- 20 Located relatively to the stitch cam 204, as 25 illustrated in the drawings, is a guard cam 208 which acts upon the needles in conjunction with the wrapping. This cam comprises two run-down portions 210 and 214 and is cutaway at its intermediate lower side as indicated at 212 for reasons which will be obvious hereafter.
- 25 A ring of cams indicated at 216 serve to act upon the upper jacks 10 being provided in a continuous ring primarily merely to hold the jacks 30 in position within the grooves of the needle cylinder. The portion active on the jacks is indicated at 218. These cams also have active upper surfaces to raise the needles after the drawing of stitches.
- 35 A cam 220 serves to raise the lower jacks to 40 elevate the needles for wrapping. This cam includes a slope 222 serving to raise the shoulder 18 to the horizontal level indicated at 224. Beyond 224 a further rise 226 is provided. This is followed by a depression 228 and a second rise 230. An inwardly sloping portion 232 on the cam 220 serves to rock the lower ends of the jacks 14 inwardly following the wrapping operation and 45 during the lowering of the jacks due to their engagement by the upper jacks 10 which are forced downwardly by the cam portion 218.
- 45 A safety cam 234 is provided to prevent overrun of those jacks which are depressed by the cam 218. This cam serves to hold the jacks in 50 position for later engagement by the cam 236 which is provided with a sloping upper surface 238 designed to engage the shoulders 18 and align jacks so that the butts 16 thereon will cooperate properly with the various fingers 242.
- 55 Prior to engagement of the shoulders 18 with the cam 236, all of the lower jacks 14 are rocked to force their upper ends inwardly by the action 55 of a cam 240.
- 60 The fingers 242 which serve to provide selection for wrapping are controlled in the fashion indicated in the Shelmire application referred to above, namely, by a trick wheel which is intermittently stepped about under control of a pattern chain. If a jack 14 is rocked by a finger 65 242 then its shoulder 18 will fail to engage the slope 222 of the cam 220 and consequently the corresponding needle will not be raised to receive wrap yarns but will eventually engage the rise of cam 204 and pass thereover taking the main yarn 70 and being lowered to draw stitches by cam 206. On the other hand, if a jack is not engaged by a finger 242, it will rise over cam 220 first occupying a level as determined by 224, at which level the corresponding wrap finger may be rocked to carry 75 a yarn outwardly, and then it will rise to the
- level 226 while the same wrap finger is moved inwardly. This action will occur if the wrap finger associated with the particular needle in question is provided with an upper butt 87 so as to be engaged by the cam 90. The needle will now be at such level that its butt will engage the cam surface 210 so that the needle will be lowered forcing the lower jack downwardly to bring its shoulder 18 into the depression 228. If the wrap finger associated with the needle was of the type 80 10 then movement of the yarn outwardly will occur at a position corresponding to 228 while movement inwardly will occur when the needle is raised by the riding of the jack 14 upwardly at 15 230. After the jack passes the position 230 it is 20 forced downwardly by the action of 218 on the butt 12 of the corresponding intermediate jack 10. At the same time the shoulder 18 is engaged by the cam face 232 and the lower end of the jack is rocked inwardly. The corresponding 25 needle is depressed by the cam surface 214 and then passes through the knitting wave.
- It will thus be seen that needles associated with fingers 81 will be wrapped by the action of cams 90 and 118. On the other hand, needles associated with fingers 80 will be wrapped by the action of cams 92 and 120. Assuming that a set of fingers 81 of an angular extent greater than that between the active portions of cams 90 and 92 precede a set of fingers 80, the last of the 30 set of fingers 81 will have been returned by the cam 118 to a position within the needle circle for a substantial angular interval prior to the movement of the leading fingers 80 outwardly through the needle circle by the action of cam 35 92. During this interval there will be no wrap finger anywhere in the circle extending between pairs of needles. Shogging may accordingly be effected in this interval. On the other hand, all of the needles may be wrapped inasmuch as in 40 spite of the interval during which no fingers are being moved, all of the fingers are at sometime moved to produce wrapping of needles.
- In view of the fact that it is the needle cylinder which is definitely timed with respect to the 45 other parts of the mechanism, and more particularly the shogging devices, the interval referred to above during which no fingers are located between pairs of needles must be somewhat greater than that corresponding to the 50 angular movement of the needle cylinder during shogging. This is necessary because the boundary between the two types of wrap fingers is displaced in accordance with the shogging. The interval must accordingly be equal to the 55 interval required merely for the displacement of the wrap finger supporting head relative to the needle cylinder by the ratchet mechanism plus the maximum displacement which the wrap finger may undergo relative to the needle cylinder from their central position.
- A statement was heretofore made relative to the 60 disposition of the wrap fingers 80 and 81 about the support. As will be seen from the above, it is not necessary that there should be 65 180° of each type of finger. This arrangement would be used when it was considered desirable to avoid wrapping say through the high splice or the foot of the stocking while permitting wrapping to continue through the instep. In 70 such case, during the formation of the high splice or foot either one of cams 90 or 92 would be rendered inactive. Of course, alternatively, wrapping may be controlled by the proper selection of needles for wrapping under the action 75

of the fingers 242. In other cases, however, the disposition of fingers 80 and 81 may vary within wide limits. For example, one set of fingers may be used where it is desired to produce clocks by 5 local wrapping without wrapping entirely around the stocking.

The general operation of the machine with respect to the production of various parts of the stocking need not be described in greater detail 10 since it is fully brought out in connection with the present machine in the Shelmire application noted above.

It will be clear that numerous variations may be made in details of the embodiment of the invention without departing from the scope thereof 15 as defined in the following claims.

What I claim and desire to protect by Letters Patent is:

1. A knitting machine including a rotating 20 needle cylinder, needles carried by the cylinder, wrap fingers arranged to carry wrap yarns about needles, a carrier for the fingers rotating with the needle cylinder, spaced means for actuating the wrap fingers to cause them to carry yarns 25 about needles at either of two spaced points, one of said means actuating certain of said fingers and the other of said means actuating other fingers, and means for shogging the carrier relatively to the needle cylinder in a plurality of steps 30 in each direction corresponding to the angular spacing of adjacent needles during a time when no wrap fingers are being actuated at either position, said shogging means including means for positively arresting shogging movements in 35 both directions whereby the spacing of the two wrap points is reduced to a minimum.

2. A knitting machine including a rotating needle cylinder, needles carried by the cylinder, wrap fingers arranged to carry wrap yarns about 40 needles, a carrier for the fingers rotating with the needle cylinder, spaced means for actuating the wrap fingers to cause them to carry yarns about needles at either of two spaced points, one of said means actuating certain of said 45 fingers and the other of said means actuating other fingers, said means including levers having active portions arranged to engage the wrap fingers at the two points, and means for shogging the carrier relatively to the needle cylinder 50 in a plurality of steps in each direction corresponding to the angular spacing of adjacent needles during a time when no wrap fingers are being actuated at either position, said shogging means including means for positively arresting shogging 55 movements in both directions whereby the spacing of the two wrap points is reduced to a minimum although wrapping of all the needles may be effected.

3. A knitting machine including a rotary 60 needle cylinder, needles carried by the cylinder, wrap fingers arranged to carry wrap yarns about needles, a carrier for the fingers rotating with the needle cylinder, spaced means for actuating the wrap fingers to cause them to carry yarns 65 about needles at either of two spaced points, one of said means actuating certain of said fingers and the other of said means actuating other fingers, means for supporting both the wrap finger carrier and said means whereby they are 70 movable away from the needle cylinder, controlling means for the wrap finger actuating means automatically becoming effective to control the actuating means when the wrap finger carrier and actuating means are brought into active positions, and means for shogging the carrier relatively to the needle cylinder 75 in steps corresponding to the angular spac-

rier relatively to the needle cylinder in steps corresponding to the angular spacing of adjacent needles during a time when no wrap fingers are being actuated at either position.

4. A knitting machine including a rotary needle 5 cylinder, needles carried by the cylinder, wrap fingers arranged to carry wrap yarns about needles, a carrier for the fingers rotating with the needle cylinder, spaced means for actuating the wrap fingers to cause them to carry yarns about 10 needles at either of two spaced points, one of said means actuating certain of said fingers and the other of said means actuating other fingers, means for supporting both the wrap finger carrier and said means whereby they are movable away from 15 the needle cylinder, controlling means for the wrap finger actuating means automatically becoming effective to control the actuating means when the wrap finger carrier and actuating means are brought into active positions, and means for shogging the carrier relatively to the needle cylinder in a plurality of steps in each direction corresponding to the angular spacing of adjacent needles during a time when no wrap fingers are being actuated at either position, said shogging 20 means including means for positively arresting shogging movements in both directions whereby the spacing of the two wrap points is reduced to a minimum although wrapping of all the needles 25 may be effected.

5. A knitting machine including a rotary needle cylinder, needles carried by the cylinder, wrap fingers arranged to carry wrap yarns about needles, a carrier for the fingers rotating with the needle cylinder, spaced means for actuating the wrap fingers to cause them to carry yarns about 30 needles at either of two spaced points, one of said means actuating certain of said fingers and the other of said means actuating other fingers, said means including levers pivoted on a common axis 35 and having active portions arranged to engage the wrap fingers at the two points, means for supporting both the wrap finger carrier and said means whereby they are movable away from the needle cylinder, controlling means for the wrap finger actuating means automatically becoming 40 effective to control the actuating means when the wrap finger carrier and actuating means are brought into active positions, and means for shogging the carrier relatively to the needle cylinder 45 in a plurality of steps in each direction corresponding to the angular spacing of adjacent needles during a time when no wrap fingers are being actuated at either position, said shogging means including means for positively arresting shogging 50 movements in both directions whereby the spacing of the two wrap points is reduced to a minimum although wrapping of all the needles may 55 be effected.

6. A knitting machine including a rotating needle cylinder, needles carried by the cylinder, wrap fingers arranged to carry yarns about needles, a carrier for the fingers rotating with the needle cylinder, means for selectively actuating the wrap fingers to cause them to carry yarns about needles 60 at either of two spaced points, means for selectively raising at a single point preceding both of said spaced points all of those needles which are to be wrapped in the formation of any course, 65 whereby following the raising of needles selective wrapping thereof is determined solely by selective control of the wrap fingers and means for shogging the carrier relatively to the needle cylinder in steps corresponding to the angular spac- 70 75

ing of adjacent needles during a time when no wrapping is taking place.

7. A knitting machine including a rotating needle cylinder, needles carried by the cylinder, wrap fingers arranged to carry yarns about needles, said wrap fingers being arranged to contact with the needles to effect wrapping by passing outwardly through the needle circle at one side of the needles to be wrapped and inwardly at the other side thereof, a carrier for the fingers rotating with the needle cylinder, means for selectively actuating the wrap fingers to cause them to carry yarns about needles at either of two spaced points, means for selectively raising at a single point preceding both of said spaced points all of those needles which are to be wrapped in the formation of any course, whereby following the raising of needles selective wrapping thereof is determined solely by selective control of the wrap fingers and means for shogging the carrier relatively to the needle cylinder in steps corresponding to the angular spacing of adjacent needles during a time when no wrapping is taking place.
8. A knitting machine including a rotating needle cylinder, needles carried by the cylinder, wrap fingers arranged to carry wrap yarns about needles, a carrier for the fingers rotating with the needle cylinder, means for actuating the wrap fingers to effect wrapping of needles at spaced points, certain of the needles being wrapped at one of such points and other needles being wrapped at the other of such points, and means for shogging the carrier relatively to the needle cylinder in a plurality of steps in each direction corresponding to the angular spacing of adjacent needles during a time when no wrapping is taking place, said shogging means including means for positively arresting shogging movements in both directions, whereby the spacing of the two wrap points is reduced to a minimum although wrapping of all the needles may be effected.

9. A knitting machine including a rotating needle cylinder, needles carried by the cylinder, wrap fingers arranged to feed wrap yarns to needles, a carrier for the fingers rotating with the needle cylinder, means for selecting needles to be wrapped from others not to be wrapped at one point, means for actuating the wrap fingers to cause them to present wrap yarns to needles selected to be wrapped at either of two spaced points following said point, one of said means actuating certain of said fingers and the other of said means actuating other fingers, and means for shogging the carrier relatively to the needle cylinder in a plurality of steps in each direction corresponding to the angular spacing of adjacent needles during a time when no wrapping is taking place, the angular spacing of said wrap finger actuating means being greater than the angle through which the needle cylinder moves during shogging.

10. A knitting machine including a rotating needle cylinder, needles carried by the cylinder, wrap fingers arranged to feed wrap yarns to needles, a carrier for the fingers rotating with the needle cylinder, means for selecting needles to be wrapped from others not to be wrapped at one point, means for actuating the wrap fingers to cause them to present wrap yarns to needles selected to be wrapped at either of two spaced points following said point, one of said means actuating certain of said fingers and the other of said means actuating other fingers, and means for shogging the carrier relatively to the needle cylinder in a plurality of steps in each direction corresponding to the angular spacing of adjacent needles during a time when no wrapping is taking place, said shogging means including means for positively arresting shogging movements in both directions, whereby the spacing of the two wrap points is reduced to a minimum although wrapping of all of the needles may be effected.
